UNITED STATES PATENT OFFICE.

HARRY PHILIP MUSSEN, OF GRAND RAPIDS, MICHIGAN.

DIVISIBLE PASSENGER-RECEIPT AND AUDITOR-COUPON RAILROAD-TICKET.

SPECIFICATION forming part of Letters Patent No. 577,622, dated February 23, 1897.

Application filed April 15, 1896. Serial No. 587,675. (No specimens.)

To all whom it may concern:

Be it known that I, HARRY PHILIP MUSSEN, a citizen of the United States, residing at Grand Rapids, in the county of Kent and State 5 of Michigan, have invented a new and useful Divisible Passenger-Receipt and Auditor-Coupon Railroad-Ticket, of which the following is a specification.

This invention has relation to that class of railroad-tickets which aim to secure both the passenger and the company against fraudulent practices on the part of dishonest conductors and employees who collect fares in cash between way and other stations, and who not infrequently overcharge the passenger and convert a part of the cash collections to their own use, and which provide a means for the adjusting and settling of accounts by the auditor.

20 The purpose of this invention is to provide a ready and convenient means for attaining the aforesaid ends and which will be a sure check to dishonest practices and enable the conductor to separate the ticket on proper lines by a forward and continuous pull without appreciably increasing the time ordinarily required to make collections.

For a full understanding of the merits and advantages of the invention reference is to be had to the accompanying drawings and the following description.

Figure 1 is a face view of the improved ticket. Fig. 2 is a view similar to Fig. 1, showing the ticket divided as in practice.

35 The ticket is rectangular in form and is constructed of a single sheet of paper, cardboard, or other suitable material and is subdivided into a series of spaces. The space A at the left-hand end of the ticket is designed to receive any matter to be printed or written thereon and forms an essential part of the auditing-coupon and contains the names of the stations between which the ticket is issued and used, and also bears the designating number or character for identifying the parts of the ticket after the latter has been separated.

The space B to the right of the space A is subdivided by horizontal and vertical break-lines *a* and *b* to facilitate the separation of the ticket when required. The numerals "1" to "5" are placed in a horizontal line at the

head of the space B, and each numeral occupies the space formed between adjacent break-lines *b*. These numerals range consecutively from right to left and represent dollars. The ticket shown is for five dollars; but it will be understood that the amount may be increased by supplying additional numerals at the head of the space B, the remaining portions of the ticket being preserved intact.

To facilitate the reckoning of the auditing-coupon, subordinate numerals extend in line with and immediately below the first-mentioned numerals and range consecutively from right to left, the numeral "1" being placed beneath the numeral "2," as shown.

The space at the right-hand side of the ticket is subdivided into parts C and D, the part C bearing the name of the road issuing the ticket, the contract, receipt, or other matter, the name of the official, and the designating number or character corresponding to that imprinted upon the space A. The part 75 D is divided into squares by extending the break-lines *a* and *b*, the squares being ten horizontally across the ticket and ten high, whereby in all one hundred squares are provided. These squares represent fractional 80 parts of a dollar and bear numerals from "1" to "99." Beginning at the upper right-hand corner the squares are numbered consecutively to the left from the top to the bottom horizontal line of squares, as shown. Each 85 vertical and horizontal column of numerals contains just ten figures, which range consecutively from right to left and decimals from top to bottom.

When the conductor collects a fare, the 90 ticket is divided so that the receipt portion shows exactly the amount paid by the passenger, and the remaining part is the auditing-coupon and indicates the amount collected and one cent more in the event of the fare 95 containing a fractional part of a dollar. When the fare is greater than a dollar, the lowest subordinate numeral at the top of the space B indicates the amount in dollars, the fractional part of a dollar being indicated by 100 the lowest numeral on the part D, it being remembered that a deduction of one cent must be made in each case where the fare contains a fractional part of a dollar to cor-

rectly indicate the true amount collected. The receipt part indicated in Fig. 2 represents a collection of two dollars and thirty-four cents, whereas the auditing-coupon represents two dollars and thirty-five cents, from which one cent is to be deducted to obtain the correct amount.

Having thus described the invention, what is claimed as new is—

- 10 o A new article of manufacture, a divisible passenger-receipt and auditor-coupon railroad-ticket comprising a middle and end spaces, one end space bearing the names of the stations, a designating-character and de-
15 sired matter, the other end space having an upper part upon which are placed a designating-character, the receipt and other matter, and a lower part which is subdivided by vertical break-lines extending from the said upper
20 part to the lower edge of the ticket and horizontal break-lines, forming squares or spaces

ten to a side and numbered consecutively in horizontal groups of ten from right to left from the upper right-hand corner to the lower left-hand corner, and ranging decimal in vertical lines from top to bottom, and the middle space having the said horizontal break-lines extending across to the first-mentioned space, and having vertical break-lines extending from the top to the bottom of the 30 ticket, the heads of the vertical spaces having dollar-indicating numerals consecutively arranged in horizontal alinement, substantially as specified.

In testimony that I claim the foregoing as 35 my own I have hereto affixed my signature in the presence of two witnesses.

HARRY PHILIP MUSSEN.
